UNITED STATES PATENT OFFICE

2,375,649

OIL BURNER

James R. Hawley, Seattle, Wash.

Application July 21, 1941, Serial No. 403,345

2 Claims. (Cl. 158—36)

This invention relates to oil burners, and more particularly to oil burners of the types now generally used in connection with plants for the heating of homes, commercial establishments and for analogous uses, and which are designed for the burning of what is generally referred to as "heavy" fuel oil; it being the principal object of this invention to adapt the principle of atomization to the use of heavy fuel oils by applying heat and mechanical pressure to small capacity nozzles to insure satisfactory atomization and efficient operation without coking or other fouling of the burner.

The present invention is a continuation in part of the subject matter of my copending application, filed on August 21, 1939, under Serial No. 291,148, now Patent No. 2,255,318, September 9, 1941.

It has been recognized in the use of heavy fuel oils that better atomization and greater heating efficiency will be obtained in the burning operation if the fuel oil is warmed up before it is atomized for ignition in the combustion chamber. In some burners, provision has been made for such heating of the oil, but usually, this takes place at some point remote from the actual point of atomization. Remote heating is accompanied by certain disadvantages, which the present invention has overcome.

One of the disadvantages in the preheating of the fuel oil at a point remote from the point of atomization, is the resultant loss of heat from the preheated oil as it flows to the point of atomization, and the corresponding loss of burning efficiency. Where attempts have been made to overcome this drop in efficiency by preheating the oil to a higher degree, there has been noted the very objectionable result of coking of the oil in the preheating coils, requiring that they be periodically cleaned of such coke or carbon, or that the apparatus ultimately be replaced because of resultant deterioration.

The coking of oil in the pipes, or tubes in which preheating is effected, results in small particles of coke being dislodged from the tube walls and carried to the atomizing nozzle, either partially or entirely closing its discharge orifice and thus rendering the burner inoperative or inefficient and presenting a serious hazard to safety. Furthermore, this formation of coke, and the clogging of nozzles or valves frequently results in the dripping of oil and a further hazard to safety.

In view of the above mentioned and other disadvantages of remote heating of the oil, it has been the principal object of this invention to pro-

vide an oil burner wherein the oil, delivered from a source of supply remote from the burner, is preheated within the burner itself to a degree reasonably close to its vaporization temperature and at a point immediately adjacent the nozzle orifice whereby it is atomized and discharged into the combustion chamber, thus avoiding those objectionable features of nozzle fouling, heat loss and coking that were previously mentioned.

It is also an object of this invention to provide a burner embodying the features previously mentioned and wherein an oil delivery pipe leads from the oil delivery and pressure pump to the atomizing nozzle, and a check valve and control valve are incorporated in this pipe near the pump and nozzle, respectively, whereby oil contained in the pipe between these valves will be confined under pressure, thus permitting it to be brought to a higher temperature, without vaporization or carbonization, and thus insuring easier and quicker starting of the burner incident to heating and subsequent opening of the control valve.

Still another object of the present invention is to provide an oil burner which embodies there-in a converter for quick and effective heating of oil thus to reduce with safety the time required for proper starting of the burner to a minimum.

Another object of the invention is to provide an extended heating passage of helical formation in the converter tube to give maximum efficiency and proper heating of oil in the minimum time.

In accomplishing these and other objects of the invention, I have provided the improved details of construction, the preferred forms of which are illustrated in the accompanying drawings, where-in—

Fig. 1 is a sectional view, in a vertical plane, of an oil burner embodying the present invention.

Fig. 2 is a plan view of the same, showing the fan and fan housing in horizontal section, and a portion of the air blast tube broken away.

Fig. 3 is an enlarged, longitudinal section of the receiving end portion of the converter tube and particularly illustrating the mounting of the valve operating solenoid thereon.

Fig. 4 is an enlarged, sectional detail of the discharge end of the converter, showing the nozzle control valve.

Fig. 5 is a cross section on line 5—5 in Fig. 4.

Fig. 6 is an enlarged sectional detail of the nozzle end of the converter.

Fig. 7 is a diagrammatic showing of the oil pipe connections between source of supply and converter.

Fig. 8 is a diagram of the electrical system for the burner.

The present improvement is not intended to be confined in its use to any particular make of burner, but to be applied to all burners which are of a type to which it may be economically adapted. In the typical construction, herein illustrated, the burner comprises a housing containing a fan, driven by electric motor, for the forcible delivery of air through an air blast tube into the combustion chamber of a furnace with which the burner may be associated. Located coaxially within the air blast tube is an electrically heated oil delivery unit to which I will hereinafter refer as a "converter tube." Oil is delivered to the converter tube by means of a motor driven pump, at a constant predetermined pressure and is discharged therefrom into the air blast as it enters the combustion chamber through a valve controlled nozzle orifice.

The oil is heated in the converter by flow of electric current through a resistance coil which closely surrounds the oil delivery tube, and to facilitate this heating, the oil is caused to flow through an elongated helical channel leading up to the nozzle. This also causes the oil to reach its maximum temperature at the entrance to the discharge orifice.

The actual delivery of oil from the converter is under control of a valve located at the entrance to the nozzle, and controlled automatically through the energization of a solenoid which, in turn, is under control of conventional or special thermostatic devices, for example, such as were disclosed in the previously mentioned application, Ser. No. 291,148.

Referring now more in detail to the drawings—

In a preferred form of construction of oil burner embodying the present invention, there is a rectangular base section 10 which mounts a fan housing 11 thereon. The base section is equipped within its four corner portions, with vertical supporting legs 10a, having feet 10b. These legs are threaded through mounting brackets 10c fixed in the base section and may be vertically adjusted to level and maintain the burner at a set position.

The fan housing 11 rests upon and is rigidly fixed to the base 10 and within its upper portions contains a fan 14 of squirrel cage type, equipped with a hollow hub portion 14a whereby it is mounted upon the end of the drive shaft 15a of an electric motor 15. The motor, in turn, is fixedly mounted upon the side wall of the housing 11 by a plate 16.

Air is admitted to the fan through a side wall opening 11x in the housing wall that is opposite that on which the motor is mounted, as noted in Fig. 2.

Mounted on the side wall of the housing 11 about the wall opening 11x is a bracket 19 and operatively supported by this bracket is a fuel pump designated in its entirety by numeral 18. This pump has a drive shaft 18a, coaxially aligned and keyed within the fan hub and effecting a driving connection therethrough with the drive shaft of the electric motor, so that the pump is continuously in operation.

Fixed to the pump housing, at the outside, is an oil filtering chamber 20 connected by a conduit 21 with a source of supply of fuel oil, not herein shown. The intake side of the pump housing, as noted in Fig. 7, communicates through a passage or port 22 with the filter chamber and its outlet port 23 communicates

with a duct 23' leading to an adjustable pressure regulating valve 24 from which a feed conduit 25 leads to the receiving end of the converter 26, later to be described in detail.

In the connection between the pressure pump and the converter there is interposed an expansion chamber and strainer, designated in general at 28.

The pump, in operation draws oil from the filter chamber and delivers it at a predetermined, set pressure, past the regulating valve 24 to the strainer 28 and from the latter to the converter 26.

The lower portion of the fan housing 11 is rectangular in cross section, and is slightly larger than the upper portion, converging at its forward side to a cylindrical neck 11b from which a cylindrical air blast tube 13 extends for directing the air supplied by the fan 14 to the combustion chamber of the furnace with which the burner is used. At its delivery end, the air blast tube is fitted with a nozzle member 13' for concentrating the blast and this nozzle may, if desired, be equipped with fins or deflectors, not shown, for causing a whirling or swirling delivery of the mixture into the combustion chamber.

Disposed horizontally within the housing 11 and coaxially of the blast tube 13 is the "converter" oil heating tube 35. The rearward end of this heating tube extends through the rearward wall of the housing 11 and is there provided with a tubular fitting 36 to which the oil delivery conduit 25, leading from the pump 18, connects for supplying oil to the heating tube. At its forward end, the tube 35 is equipped with an atomizing tip 38 and this is disposed, as noted in Fig. 1, just within and centrally of the delivery end of the blast tube.

Mounted on a side wall of the housing 11, below the motor 15, is a transformer 42, and extending from this are circuit wires 43 and 44 leading into the housing and along the converter and terminating in ignition points 46 and 47 located adjacent the atomizing nozzle and between which points a spark may be caused to jump for igniting the combustible mixture as is the usual procedure.

Mounted upon the fitting 36 and disposed vertically thereon, is a solenoid 40 designed for control and operation of an oil delivery valve at the delivery end of tube 35, as presently will be explained.

As seen in Fig. 3, the solenoid 40 comprises a coil 40' that is enclosed within a housing 48, and is disposed about a cylindrical, liquid-tight, tubular dome 50, which is threaded into the fitting 36. The dome 50 contains a steel block 51 which operates as a solenoid core, and, as here shown, will be drawn upwardly upon energization of the coil.

A link 52 is pivotally connected to the lower end of the core, as at 53, and at its lower end, the link is pivotally attached, as at 54, to a lever 55 used in the control of the oil valve in the converter tube, as presently will be explained.

The tube 35, as noted in Fig. 3, is threaded into a nipple 56 which is attached to the fitting 36 by a coupling union 57. A tubular fitting 58 is inserted in the fitting 56 and is held in place by the nipple 56 and the union 57. This fitting 58 is shouldered to limit its insertion in part 36 and forms a leak-tight connection with the nipple 56; and, slidably contained within the coaxial bore 61 in the fitting 58, is a rod 60. It will be noted that the fitting 58 is longitudinally

slotted at its top side and inner end within part 36, as at 62, to receive the end of the lever 55, and this lever 55 is pivotally mounted in the slot 52 by a pin 63. Also, it will be noted that the rearward end of the rod 60 is slotted, as at 64, and receives the pivoted end portion of the lever 55 and that a pin 65 is fixed in the rod 60 and extends through the slot, and that a notch or recess 66 in the lower edge of the lever receives the pin 65 therein. Ports 67 in the fitting 58 open into an enlarged central bore 68 for an unrestricted passage of oil therethrough to tube 35.

With this arrangement of parts, energization of the solenoid 40 causes an actuation of the lever 55 whereby the rod 60 will be pulled outwardly. As will presently be understood, this opens the nozzle valve for delivery of oil from the converter nozzle.

Disposed lengthwise within the tube 35 is a filler or spacer tube 70, provided at opposite ends with closure fittings 71-71' which seal the tube liquid-tight. These closure fittings are provided with annular outer end portions 72-72' of a diameter slightly greater than that of tube 70, which have an easy sliding fit within the tube 35. These annular portions 72-72' are provided with a plurality of notches or grooves 73-73' to allow a free and unrestricted passage of oil therethrough and about the tube 70. Furthermore, the closures at the two ends of the tube 70 are counterbored, as at 75-75' from their outer ends to a diameter and depth suitable to loosely receive, at one end, an end portion of the rod 60, and at the other end, the valve plunger 86. The rod 60 and plunger are fixed in place respectively by pins 76-76'.

The rather narrow annular passage which is formed between the oil tube 35 and the filler tube 70, and which extends substantially the full length of the converter, contains a helical coil of copper wire 87. This wire is of such diameter that the convolutions of the coil all contact closely with the tube surfaces and the convolutions are slightly spaced apart, so that the coil thus provides an elongated helical channel through which the oil must flow in its passage to the burner nozzle. In the usual size of burners, this wire coil provides an oil channel approximately one-eighth of an inch wide and from 150 to 190 inches long and presents a total of approximately 120 to 180 square inches of heating surface.

Controlled heat is applied to the converter tube through use of an electrical heating element. In the present instance, I prefer to use a nichrome ribbon element 90, which is wound about the tube 35, being electrically insulated therefrom by an interposed mica ribbon 91. Overlying the element is a covering 92, of plastic asbestos, or the like, which serves both as an insulator and as a means of confining heat in the converter.

Circuit wires 93 and 94 lead to the opposite ends of the heating element. These connect with a suitable source of electrical energy which may be automatically applied through use of thermostatic switches, later described.

Referring to Fig. 6, it will be seen that there is a sleeve 95 tightly pressed into the outer end of tube 35, and the tube is threaded into a cap 96, into which cap the atomizer spray tip or nozzle 38 is threaded. Flow of oil to the atomizer or nozzle 38 is under control of a valve device that is located in the forward end of the tube 35, within the cap 96 and adjacent to the spray tip 38.

The valve device comprises a valve seat member 105 which is threaded into an inner end opening provided in the spray tip 38. Continuing from the valve plunger 86 is a valve stem 106 slidably contained in a counterbore within an inwardly extending portion of the valve seat member.

The valve stem or plunger 106 has a tapered forward end portion 106a adapted to close against a valve seat formed by a tapered bore 105a in the member 105 to cut off the flow of heated oil to the atomizing nozzle. It will be understood that upon energization of the solenoid, the core 51 will be lifted, and the lever 55 will be actuated to pull the tube 70 outwardly, thus to unseat the valve stem from the seat 105a. Also, upon de-energization of the solenoid, the core 51 will drop, and this action will move the valve stem to close the passage. Flow of oil to the nozzle through fitting 105 is permitted by reason of a plurality of ports 105b in its inner end portion, inside the valve seat, as noted in Fig. 4. A screen 105x is wrapped about the inner portion of the member 105 to catch any foreign matter that might be apt to clog the valve or nozzle, or prevent the valve from seating.

A thermostat bulb, designated by reference numeral 130, is disposed at the outside of tube 35 and near the discharge end of the converter as in Fig. 4. This bulb is in contact on one side with the tube and on its other side with the heating element. A small tube 131 leads from the bulb 130 to transmit pressure of expandible medium used in the bulb to an adjustable thermostatic switch 184 to provide for control of the latter, as will presently be explained.

In Fig. 8, 190 and 191 designate power lines leading from a source of low voltage current, while 192 and 193 designate power lines supplying high voltage current. The electric motor 15 has one side connected by a line 194 with line 193, and its other side connected by a line 195 with a contact 196 on a stack switch 197. The transformer 42 has one side connected by a wire 198 with the circuit line 193 and its other side connected by a wire 199 with the contact 200 of the stack switch.

The stack switch has a switch arm connected by a line 201 with line 192, and this arm comprises parts 202 and 203, adapted to open or close as a unit, and on closing, to engage the contacts 196 and 200 and simultaneously close the high voltage circuit through motor 15 and the transformer 42. The switch members 202 and 203 are operable to closed position under control of a solenoid 205 having a circuit connection 206 with line 190 and a connection 207 through a time delay switch 208 which will electrically connect the wire 207 with a circuit wire 209 leading to circuit wire 191.

The room thermostat, which is generally the instrument under which automatic control of the burner is placed, is designated at 210, and has one side connected by a line 211 with circuit line 191, and its other side connected through a wire 212 to a solenoid coil 213 of a solenoid switch 224, and then through a wire 212a to one side of a lock-out switch 214, which has its other side connected by a wire 215 with the line 190.

The time delay switch 208 includes a heating element 220 which functions when current is passed therethrough to heat a bi-metal strip to effect the closing of switch 208 and thus connect the lines 207 and 209 and energize the solenoid coil 205 in the stack switch 197. This solenoid

coil 205, upon being energized, closes the switch elements 202 and 203 in the stack switch to energize the ignition transformer 42 and start the motor 15 and simultaneously operate the valve solenoid 40. The valve solenoid 40 has a connection 221 with line 193 and a connection 222 with line 195.

The lock-out switch 214 is opened by heating of a bi-metal strip connected in the stack switch to open the lock-out switch a short predetermined interval of time after the closing of switches 202 and 203 if the spiral bi-metal element 197a of the stack switch is not affected by the heat of combustion.

In heating a home, when the room temperature falls below that for which the room thermostat 210 is set, the switch 210a therein closes, thereby energizing the solenoid coil 213 in the relay 224 which causes the closing of the switches 225 and 226. These latter switches close the circuit to the burner thermostatic switch 184 through the lines 229 and 230, and to the time delay relay switch 208 through the lines 232 and 233.

The oil heating element 90 connects with the switch 184 through wires 93 and 94, and the circuit is completed through the normally closed switches 184a and 184b to energize the heating element. Upon the heating of the element, the heater tube and the oil contained therein finally reach a certain predetermined temperature, and the thermostat bulb operates through the connecting tube 131 to open the switches 184a and 184b in the switch 184. When the converter falls below a certain predetermined temperature, the thermostat bulb operates to close the switches to maintain a circuit that keeps the oil at a substantially constant temperature.

Simultaneous with the energization of the oil heater element, the time delay relay heater element 220 is energized, and after a predetermined period of time, the switch 208 is actuated to a closed position, thereby closing the circuit to the solenoid 205 in the stack switch. During this period of time, the heater element is heating the oil in the tube 35 to the point where atomization for combustion is most readily established and maintained most efficiently and economically. When the solenoid 205 in the stack switch is energized, it operates to close the switches 202 and 203 whereupon the circuits are closed both to the valve operating solenoid 40 and to the motor, thereby opening the valve and starting the pump for the delivery of fuel under pressure, and a blast of air through the tube 13 to support combustion, at the same time furnishing current to the ignition transformer for ignition of the fuel mixture. Upon combustion being established, it will continue until one of the controls automatically calls for a shut down. The heating element, however, will remain energized to heat the oil to a predetermined temperature, or will be turned off and on intermittently to maintain a substantially constant heat under control of the thermostat bulb and the switch 184.

In a normal operation, when the room ther-

mostat 210 is satisfied, the switch 210a is opened, thereby de-energizing the solenoid coil 213 for opening the switches 225 and 226 in the relay 224. This opens the circuit to the heater, and the time delay relay element 220. However, in this construction, the time delay relay will not open for a predetermined interval of time, thereby maintaining the operation of the motor 15, the pump 20 and holding the valve solenoid 40 energized until the circuit is opened. This allows the burner to scavenge itself of hot oil in the heater tube and dissipate the heat of the tube itself. This provides that the oil temperature in the tube will be reduced and that the tube itself will be cooled to a safe temperature below which coking of the oil therein will not take place.

The particular advantages of this burner are to be found in the provision for heating the oil adjacent its point of use and to a maximum at the nozzle. Also, in confining the oil under pressure at all times between the nozzle and pump so that at the instant the nozzle is opened, the oil is at atomizing pressure, thereby being instantly ignitable, and preventing discharge of oil into the firebox before ignition takes place, as would be the case in the event that an atomizing pressure had to be built up after the nozzle valve was opened.

Having thus described my invention, what I claim as new therein and desire to secure by Letters Patent is:

1. In an oil burner of the character described, an oil delivery tube, an oil atomizing nozzle at the discharge end of the tube, a control valve in the tube adjacent the nozzle, a filler tube operatively connected with the valve, for actuating it between open and closed positions, and positioned in the oil delivery tube centrally and coaxially thereof and setting off an annular channel between the tubes for the passage of oil to the nozzle, means for supplying oil under pressure to the receiving end of the delivery tube, a helical wire coil interposed in the annular channel and extending substantially the length of the tube and contacting with the surrounded and surrounding tubes throughout its length to provide a continuous helical channel for flow of oil to the valve, and means for shifting the filler tube for actuating the valve between closed and open positions.

2. In an oil burner, of the character described, an oil delivery tube, an oil atomizing nozzle at the discharge end of the tube, a control valve in the tube adjacent the nozzle, a filler tube operatively connected with the valve for actuating it between open and closed positions, and positioned in the oil delivery tube centrally and coaxially thereof and setting off an annular channel between the tubes for the passage of oil to the nozzle, a solenoid mounted upon the delivery tube at its receiving end and means in the tube operatively connecting the solenoid with the filler tube for actuating the valve between closed and open positions and a circuit for operating the solenoid.

JAMES R. HAWLEY.
